UNITED STATES PATENT OFFICE.

FRANZ KASPAR, OF PRAGUE, AUSTRIA-HUNGARY.

APPARATUS FOR STICKING STAMPS.

1,090,721.

Specification of Letters Patent.

Patented Mar. 17, 1914.

Application filed June 3, 1912. Serial No. 701,436.

To all whom it may concern:

Be it known that I, FRANZ KASPAR, a subject of the Austro-Hungarian Emperor, and resident of Prague, II, 1487, Austria-Hungary, have invented certain new and useful Improvements in Apparatus for Sticking Stamps, of which the following is a specification.

This invention relates to an apparatus for 10 sticking postage and other stamps.

This apparatus is constructed in such a manner that by applying it once on the place of destination of the stamp the said place is moistened and immediately afterward the stamp brought on the said place and pressed upon it.

The accompanying drawings given by way of example show three forms of embodiment of this invention and in these 20 drawings: Figure 1 is a side elevation view of the first form of embodiment of the apparatus. Figs. 2 and 3 show two axial sections of same. Figs. 4 and 5 show two horizontal sections and Fig. 6 is a detail view while Figs. 7-10 show the function of this form of embodiment.

The stamp sticking apparatus as shown by Figs. 1-5 comprises as essential parts a framework A carrying a pressure member B slid on it from above, a tiltable air pump C a moistening device D and a small box E intended to receive the block of stamps F. The framework A comprises two parallel vertical walls 1 and 2 which are bent at their lateral edges 1' and 2' and are connected with each other at the bottom by means of a frame shaped base plate 3 and at the top by means of a casing 4. These vertical walls are provided besides with vertical slots 5 and 6. The pressure member B has the shape of a prismatic casing open at its bottom and surrounding the framework without any clearing space and is guided at the borders or edges 1' and 2' (Figs. 1, 3, 5), the lateral walls 7 and 8 of the said pressure members being extended downward. Mounted in these extensions are bolts 9 and 10 which pass through the slots 5 and 6 (Fig. 3) and thus serve to make the desired connection between the framework A and the pressure member B as well as to support the air pump C presently to be described. Inserted between the casing 4 and the upper wall of the pressure member 5 is a powerful helical spring 11 which has a tendency to hold the pressure member in its

raised position (Figs. 1-3). In order to prevent this spring from being bent during the compression, a sleeve is provided in the casing 4 and another sleeve in the upper 60 wall of the pressure member the spring being guided between these two sleeves.

Removably connected with the lower wall of the casing 4 is a die shaped casing 12. To this effect the casing 4 has been provided with a guide for instance with a T shaped or dovetailed groove 13 while the casing 12 carries a correspondingly shaped extension 14 (Figs. 2, 3, 6) so that the casing 12 can be slid in the apparatus sidewise 70 in the direction of the arrow V. The casing 4 is provided inside with a yielding pin 15 while the extension 14 carries a depression 16 whereby the working position of the casing is ascertained while when a moderate 75 pressure is exerted on the casing in the direction of the arrow H the pin is raised and frees the casing thus allowing of its being slid outward. Mounted inside the casing 17 is a two armed spring the rounded ends 80 of which project from the casing. Slid on the casing 12 in a removable manner is a small prismatic box E which by the spring 17 is prevented from falling off and serves to receive a block F of loosely superposed 85 stamps. The small box is inwardly bent at two opposite edges 18 of its lower border to such an extent that the block of stamps F may be held inside the box while the lowermost stamp the image carrying side 90 of which is facing downward, is always accessible from below and can easily be sucked off by means of the pump C. In order to insert the block of stamps into the apparatus the block of stamps F is inserted 95 in the small box E outside the apparatus and imprisoned by means of the casing 12 (Fig. 6), whereafter this part i. e. the small box E, the block of stamps F and the casing 12 are slid into the apparatus in a horizontal 100 direction V, the pin 15 jerking into the depression 16 thus locking the block of stamps in its working position.

The air pump C is formed of the pump cylinder 19, the piston 20 and the valve 21. 105 The pump cylinder 19 is provided with a horizontal carrying wall 22 by means of which as well as of the bolts 9 and 10 it is coupled with the pressure member B so that when this pressure member is moved, 110 the cylinder performs in turn a downwardly and upwardly directed motion. The wall

22 is provided with a trident 23 (Figs. 3 and 8) and on the adjacent wall 1 of the framework two pins 24 are secured in such a manner that when the trident during the 5 downward or upward motion arrives at these pins the pump cylinder is rotated 180°. On the other hand a screw 25 is screwed into the wall 22 this screw serving to guide the pump cylinder in the slot 6 and engaging an enlarged part 6' of the slot when the 10 pump cylinder is rotated.

The piston 20 of the pump forms a projecting sleeve which is mounted in the pump cylinder so as to be prevented from rotating. It carries at its top a perforated dish shaped member 26 in which an india-rubber plate 27 provided with an elongated hole 28 has been mounted. Positioned between the 15 bottom of the cylinder and the disk or dish 26 of the piston is a helical spring 29 which has a tendency to push the piston out of the cylinder.

The valve 21 is mounted in the lower cylinder head, the box of this valve being sufficiently large to fill the inner chamber of the pump cylinder to the effect to reduce the clearance space. The valve box is provided with two passages 31 and 32 (Fig. 2) which are parallel to the axis of the pump cylinder and communicate with each other at 30, the 20 passage 31 opening out downward into the atmosphere while the other passage 32 opens out at 33 into the cylinder chamber. The passage 32 contains the valve ball 34 or similar member positioned between 30 and 33 this valve ball or equivalent engaging a seat, the passage being tightly closed at its top by means of a screw 35.

When in the position of rest (Figs. 1-3) 40 the spring 29 presses the piston together with the india-rubber plate against the block of stamps and the valve 21 is closed (Fig. 2) so that the chamber of the cylinder is closed on both sides.

45 As already stated the base plate 3 of the frame-work has received the shape of a frame and the moistening device D has been arranged immediately above the opening of the frame. This moistening device is composed of a water reservoir 36 and a wick 37. The latter projects from the water reservoir through an elongated hole above which a strip or rail 38 is secured by means of screws in such a manner that by pressing 50 the strip or rail to a more or less great extent against the wick the suction effect of the latter is controlled. The wick is enlarged at its opposite end so as to form a narrow cushion 39 which is mounted into a metallic frame 40. This frame is carried by means of a fork shaped carrier 41 in a rotatory manner in the bearings 42 which are secured to the top of the water reservoir. The carrier is influenced by a helical spring 60 65 43. The water reservoir is secured on a

lever 45 through the medium of arms 44 and screws, the lever is positioned outside the framework A respectively in the space 46 (Figs. 3 and 5) between the wall 1 of the framework and the borders 1' and the 70 pressure members B; it is guided in a suitable manner and suspended by means of a pin 47 from an elongated slot 48 of the framework in such a manner that it is adapted to oscillate in the directions of the 75 arrows II and IV and to be shifted downward and upward (directions I and II) to a certain extent (Fig. 2). Secured to the lever is a pin 49 which slides in the bent slot 50-51 of the pressure member B in such 80 a manner that the oblique part 50 of the slot produces the oscillation of the lever while when the said pin is engaged in the upper vertical part 51 of the slot no oscillation of the lever takes place. Inside the pressure member 85 a spring 53 is anchored to the bolt 52 this spring sliding at its opposite end at the edge 1' of the framework and being provided with two bends 54 and 55 which produce the downward and upward sliding motion of the lever and the moistening device 90 respectively.

The function of the whole apparatus is as follows: When the parts of the apparatus occupy their position of rest or when the 95 apparatus is placed upon the place of destination of the stamp (Figs. 1 and 3) the pressure member B raised by the spring 11 and the india-rubber plate 27 of the pump C is pressed by the spring 29 against the 100 block of stamps F the valve ball 34 or its equivalent closing the inner space of the pump. The cushion 39 is not applied against the surface of the paper but is at a certain distance above this surface. When 105 the pressure member B is pressed downward the bent part 54 of the spring first forces the lever 45 downward; thus the entire moistening apparatus is pushed downward until the cushion 39 arrives at the 110 paper (direction of arrow I, Fig. 2) and is applied against the said surface by the action of spring 43. Immediately afterward the pin 49 arrives in the oblique part 50 of the slot whereby the lever 45 together 115 with the water reservoir and the cushion applied against the paper are caused to oscillate (direction of arrow II, Figs. 2, 7 and 8) so that the place of destination of the stamp is uniformly moistened with water. Figs. 120 7 and 8 show by way of example a position the moistening device assumes during its oscillatory motion while Figs. 9 and 10 represent the terminal position. But in the meanwhile the pressure member B acts also 12 upon the pump cylinder 19 which at the beginning of the pressing down moves downward along a straight line while the piston 20 remains applied with the india-rubber plate 27 against the block of stamps under 125

the action of the spring 29; consequently the inclosed space or chamber of the cylinder is increased whereby a partial vacuum is produced in the cylinder owing to which

5 vacuum the lowermost stamp is caused to continue adhering to the india-rubber plate and is removed from the block (Fig. 8).

Afterward the trident 23 engages the pins 24 by means of which the entire pump together with the lowermost stamp *f* is rotated 180°; the middle position of the pump

10 during this rotation has been shown by Fig. 9. By the time when the pump assumes this position, the pin 49 arrives in the vertical

15 part 51 of the slot and the moistening device arrives in its terminal position and the place of destination of the stamp has been moistened and freed.

10 During the further pressing down of the pressure member the stamp, its gummed side facing downward, arrives on the place of destination which has been moistened, the pump cylinder continues moving along a straight line the piston is pushed in the 25 cylinder and during this motion the stamp *f* is pressed against its place of destination under the action of the spring 29. It will be readily understood that during this motion the pump space or chamber again becomes smaller and that consequently the 30 partial vacuum ceases to exist so that the valve ball 34 not being any longer held on its seat falls under the action of its own weight (Fig. 10).

35 When the apparatus is removed from the stamp stuck in position, the cylinder chamber is first increased in size but without exerting any action upon the stamp because owing to the fact that the valve is open the

40 atmospheric pressure reigns in the chamber of the cylinder whereafter the pump is thrown upward, assumes a vertical position and is pressed by the action of the spring

45 11 against the block. During this phase the chamber of the cylinder is again reduced in size the excess of air escaping from the cylinder passing under the valve ball so that during the following suction the vacuum is again produced. In the meanwhile the upper bent

50 part 55 of the spring strikes against the lever 45 whereby the latter is raised (direction of arrow III, Figs. 2, 10) and the cushion is removed from the paper. Nearly in the position shown by Fig. 9 and which the

55 pump assumes during its backward motion, the pin 49 again arrives in the oblique part 50 of the slot so that during the continuation of the upward motion of the pressure

60 member the lever 45 together with the raised moistening device oscillate back into their starting position in the direction of the arrow without touching the stamp stuck in position. This working is repeated for the sticking of every stamp; a single pressing of

the stamp causes this place to be moistened and the stamp to be stuck thereon. The small box *E* is pushed upward in proportion to the consumption of the stamps so that the remaining stamps are always tightly applied upon each other; the upward motion is automatically effected by the plate or dish 26 pressing with its projections 56 (Figs. 2, 3) upon the lower border of the small box.

75 After the stamps have been consumed or when it is desired to employ another sort of stamps the pressure member *B* is pressed down to a certain extent and the block of stamps together with the small box *E* and the casing are slid out from the apparatus and slid again into the latter after having been filled with another charge of stamps. In order to facilitate this operation a stationary abutment 57 having a sharpened lower edge 57' has been provided on the framework *A* and inside the pressure member a spring 58 provided with a sharpened upper edge 58' has been secured which spring can be actuated by means of a button 90 from the outside of the pressure member. When the spring 58 is pressed inwardly and the pressure member *B* is pressed down to such an extent that the cutting edges 57' and 58' engage each other (Fig. 7) the members of the apparatus are thus locked in such a position that the air pump is somewhat pressed downward (as shown by Fig. 8) and is not in contact with the block of stamps or the small box *E* so that the casing 100 and the block of stamps can be slid out of the apparatus and again inserted into the latter without it being necessary to hold the pressure member *B*.

Having now fully described my said invention, what I claim and desire to secure by Letters Patent, is:

1. In an apparatus for sticking stamps the combination of a framework comprising a base plate, a moistening device, means for pivotally mounting the said moistening device in the said base plate, a pressure member connected with the same framework, means for positively connecting said pressure member with said moistening device, a block of stamps, means for supporting said block of stamps on the said framework, an air pump, means for tiltably supporting this air pump in said framework, means for positively coupling the said air-pump with said pressure member the arrangement being such that during a single application of the apparatus against the place of destination of the stamp, this place is moistened by the moistening device, then freed again whereafter the stamp which has been sucked off the block of stamps by the air pump and carried downward, is applied against the said moistened place of destination, substantially as set forth.

2. In an apparatus for sticking stamps the combination with the framework of a block of stamps, means for holding said block of stamps in the said framework, an air pump cylinder, means for supporting the said air pump cylinder in a rotatory manner in said framework, a pressure member, means for slidingly connecting this pressure member with said framework, means for positively connecting said pressure member with said air pump cylinder, a sleeve shaped piston mounted in said cylinder so as to project therefrom, a perforated india-rubber plate secured to the projecting outer end of said piston, a spiral spring adapted to force the said piston outward and to apply the said india-rubber plate against the said block of stamps in the position of rest, a valve provided in the said pump cylinder and adapted to close the cylinder chamber when the apparatus is at rest the arrangement being such that at the beginning of the lowering of the said pressure member, the

said pump cylinder is pressed downward while the piston remains applied by its india-rubber plate against the block of stamps under the action of the spring, whereby a partial vacuum is produced in the pump cylinder which partial vacuum causes the lowermost stamp to be removed from the block of stamps, while, when the pump has been tilted together with the stamp and after the pump has been applied on the place of destination of the stamp with a view of sticking the stamp thereto, the said partial vacuum ceases to exist and the valve opens thus allowing the pump to move backward without exerting any further influence on the stamp, substantially as set forth.

In testimony whereof I have hereunto set my hand in presence of two witnesses.

FRANZ KASPAR.
